INTERNAL-COMBUSTION ENGINE

Application filed July 9, 1927. Serial No. 205,012.

My present invention has reference to internal combustion engines of the two-cycle type, whether double-acting or single-acting, the main objects being efficiency, simplicity 5 and economy.

The engine mechanism contemplates a great variety of uses, but it is more particularly designed to serve as the motor mechanism of a gas-actuated rock drill or percussive machine, and also as a regular reciprocating engine to supply the operative power for an automobile, aeroplane, or other mechanism; and in my explanation following I shall present and explain certain structural 15 features applicable to that form of the invention adapted to drilling operations, as well as the combinations in another form in which the engine applies its power to actuate a drive-shaft, these being obviously how- 20 ever only specimens or examples of the use and adaptability of the invention, the same selected from a long list of possible forms and uses.

The piston and cylinder are so constructed 25 and formed with chambers, ports and passages, so arranged, together with dual fuel intakes, dual explosion chambers and dual exhausts, that at each reciprocation of the piston, a fuel charge will be compressed initially 30 and transmitted to an explosion chamber for further compression and firing at one end of the engine, while simultaneously at the other end of the engine another fuel charge is being drawn into the cylinder and piston through the intake means, and the previously- 35 transmitted charge in the second explosion chamber is being finally compressed and made ready for firing, so that in the explosion chambers the charges are alternately 40 compressed and fired, and hence a propelling impulse is applied upon the opposite sides of the piston alternately, so as to effect the generation of power in a speedy, economical and desirable manner.

45 The paramount feature of the invention lies in a duplex differential piston working in a duplex differential cylinder. There are really, in one sense, two cylinders, single-acting, separated by a stationary intervening 50 partition, and arranged tandem with each

other; and likewise two pistons arranged tandem with each other in the cylinders, said two pistons being connected together for joint movement; the cylinders being duplicates of each other and the pistons being 55 also duplicates of each other; but for descriptive purposes I prefer to treat the cylinders as a single double-acting cylinder having duplicate reversely-related sections, and the piston as a single double-acting structure 60 having reversely-related sections, since it is more natural and correct to identify the mechanical members in this way, and remembering further that the cylinders and pistons may be multiplied as much as desired in 65 multicylinder engines, and also that if desired an engine may be built single-acting with only one of the cylinder sections and one of the piston sections.

Each section or half of the cylinder has an 70 inner portion of largest diameter, an intermediate portion of smaller diameter, and an outer elongated end portion of still smaller diameter, this latter portion being the main bore of the cylinder to receive the main portion 75 of the piston; so that each cylinder section has a triple differential character, and is in this respect conformable to the shape of the piston, which is likewise differential. Each piston section has an inner part of 80 larger diameter than the main outer length of the piston, said part of larger diameter corresponding to the cylinder portion of intermediate size, while the main length of the piston corresponds in cross-section with the 85 smallest bore of the cylinder in which it reciprocates. The piston sections are hollow throughout, and the tubular passages in their long main portions connect with the chambers of larger diameter in the piston-portions 90 of larger diameter, which latter chambers open directly into the widest chambers of the cylinder and remain always in open communication with said largest cylinder chambers. The parts of largest diameter of the 95 two piston sections are united by a central connecting rod which reciprocates through the stationary walls between the cylinder sections. The chambers in the largest inner portions of the cylinder sections function as 100

preliminary fuel chambers, and are provided with intake means to enable them to receive a suitable fuel and deliver it to the hollow and chambered interiors of the piston sections. The portions of the cylinder which are of intermediate size provide explosion chambers, which surround the piston, each having its own independent exhaust, and being intermittently supplied with fuel transmitted through ports in the wall of the piston, at or near the ends of the piston, into angular passages running a distance through the wall of the cylinder and entering the ends of the explosion chambers, so that the exhaust may occur as far as possible from the intake, and the scavenging of the spent products be effectively assured.

Thus in each section of the piston and cylinder there is a preliminary compression chamber for the fuel, each such chamber comprising an inner chamber in the cylinder on one side of the stationary middle division, a chamber in the larger portion of the piston and a chamber in the main portion of the piston. These preliminary compression chambers alternately receive charges of fuel during the strokes of the piston, and are to be clearly contrasted with the firing chambers, into which the partially compressed charges are forced from the preliminary compression chambers for a second and final compression preparatory to ignition. Thus each such preliminary compression chamber receives a fuel charge while the piston section to which it is related is moving away from the central division and towards one end of the machine, that is to say away from the firing chamber located adjacent to said fuel chamber; and upon each return stroke of the piston, or as each fuel chamber moves towards its firing chamber the intake ports are cut off and the entire charge which fills the several divisions of the corresponding preliminary compression chamber is compressed in the tubular portion of the piston having the smallest cross-section in readiness to be passed into the said adjacent firing chamber when the transfer ports coincide for the purpose. Hence there is a preliminary compression taking place alternately in the chambers during each return stroke of the piston; and after each primary compression in each primary compression chamber the partially compressed charge is delivered into the final compression and explosion chambers which surround the piston, or into the duplicate sections as stated, and which explosion chambers communicate with independent exhausts, it being noted that I use certain lengthened and angular passages for the purpose of affording proper channels between the interior of the piston and the firing chambers in order to provide for the proper location of the piston rings.

The invention consists essentially in the

construction, arrangement and combination of parts, substantially as will be hereinafter described and claimed.

In the accompanying drawing illustrating my invention:

Figure 1 is a side elevation of my improved internal combustion engine.

Figure 2 is a top plan view of the same.

Figure 3 is a vertical longitudinal section on the line 3, 3, of Figure 2.

Figure 4 is a longitudinal section of the left hand half of the duplex cylinder.

Figure 5 is a longitudinal section of the right hand half section of the duplex cylinder.

Figure 6 is a longitudinal section of the piston, with the connecting rod between its duplicate sections shown in side view.

Figure 7 is a cross-section on the line 7, 7, of Figure 3.

Figure 8 is a cross-section on the line 8, 8, of Figure 3.

Figure 9 is a cross-section on the line 9, 9, of Figure 3.

Figure 10 is a cross-section on the line 10, 10, of Figure 3.

Figure 11 is a cross-section on the line 11, 11, of Figure 3.

Figure 12 is a cross-section on the line 12, 12, of Figure 3.

Figure 13 is a sectional view of a starting appliance for the engine.

Figure 14 is a cross-section on the line 14, 14, of Figure 13.

Figure 15 is a sectional detail of the intake pipe system.

Figure 16 is a sectional detail on the line 16, 16, of Figure 2.

Figure 17 is a longitudinal section of an alternative form of my improved internal combustion engine, without the drill attachment, but with the piston in side view, and the engine provided with a connecting rod and crankshaft.

Similar characters of reference designate corresponding parts throughout all the different Figures of the drawing.

I will now proceed to describe the construction and operation of the cylinder and its appurtenant parts, it being understood that any engine of my design may be single or multicylinder in construction and that where there are several cylinders they may be duplicates of the one I am now describing; but in the drawing I have only thought it necessary to show a single cylinder in order to impart the fullest understanding of the invention. The terms most apt for describing my cylinder and piston, as referred to above, will be borne in mind here. Such cylinder is double-acting, (though it may be single) compresses and fires at each stroke and hence develops great power. The cylinder may be of any specific construction, dimensions and proportions. Its cooling system

may use water or other liquid, a fan, or any other means for the purpose, but I preferably build it with a multiplicity of radiating fins or flanges, as 1^a on section 1, and 2^a on section 2, which cover the surface so as to avoid some of the objections incidental to water jackets and the like, said flanges being properly proportioned to provide the radiating surface necessary for the amount of heat developed in the operation. The cylinder may be made in several castings as shown, as for example, the two sections 1 and 2, portions thereof being of larger diameter than the piston so as to provide the firing chambers that surround the piston, and other portions of other diameters to receive the piston and to provide auxiliary cylinder fuel chambers that cooperate with the fuel chambers within the piston. But it will be noted that although the differential design of the cylinder is important, yet the proportions and relative characteristics may be changed and varied within wide limits without departing from the invention, if only the differential features are made to correspond properly with the shape of the piston and the dimensions demanded by the full charge of fuel.

The cylinder sections 1 and 2 are placed end to end or tandem and are of similar construction, though reversely related, and between them is the stationary partition or diaphragm 14, having a central gland and stuffing box 15 for the sliding rod connection for the piston members. Said sections 1 and 2 are held together by the long side tie rods 67 passing through bosses on the main frame or otherwise and having suitable nuts thereon.

Cylinder section 1 has an inner part 5 of largest diameter containing fuel chamber H. See Figures 4 and 5. Chamber H is on one side of the central division 14; and cylinder section 2 has a similar inner part 5^a of largest diameter containing fuel chamber I on the other side of division 14. Each of these chambers H and I has its own intake 7 and 7^a for the fuel as I shall presently point out. Also, cylinder sections 1 and 2 have respectively portions 3 and 3^a of smaller diameter than parts 5 and 5^a and providing the explosion chambers A and B; and they have also the elongated main portions 4 and 4^a, smaller in diameter than the explosion chambers A and B, and accommodating the main tubular portions of the piston in their bore at J and K. Thus each cylinder section is triple differential in character, and preferably so, to give the proper space for fuel in proportion to the power to be generated. The walls of chambers A and B which surround the piston are extended so as to project into and be partly surrounded by the fuel chambers H and I, this result being secured by extending an integral cylindrical flange 6 from cylinder section 3 into chamber H, and a similar flange 6^a from cylinder section 3^a into chamber I, these

flanges being cylindrical and containing inlet ports 7 and 7^a for the introduction of the fuel into the cylinder and piston-fuel-chambers, there being suitable pipes or passages for delivering the fuel to the cylinder from the carburettor, as for example, see Figure 8, the pipe 23 which is integral with the ported flange 6 and opens into the interior of said flange through the aforesaid inlet port 7; and said pipe 23 branches from a pipe 24 on the side of the cylinder, see Figure 2, and designed with a similar pipe 23^a to deliver to both inlets 7 and 7^a in equal fashion, said pipe 24 having a supply connection at some suitable point as preferred. In Figure 15 a specimen means for supplying fuel to the pipe 24 is shown consisting of pipe 71 held on the member 25 by means of a screw 70 and delivering its supply into the pipe 24 which branches into the two pipes 20 and 23^a leading respectively into the inlets 7 and 7^a. The explosion chamber A has exhaust ports 21 leading into the circumferential exhaust passage 8 that discharges through outlet 26 into exhaust pipe 27, see Figure 9; while the explosion chamber B has a series of exhaust ports 22 that discharge into the circumferential passage 8^a that finds exit into the same exhaust pipe 27 running along the side of the engine as shown in Figure 2; it being seen therefore that each explosion chamber has its independent outlet for discharge for a thorough scavenging of the spent products of combustion. The various chambers of the cylinder are provided with miscellaneous draw-off cocks 68 and 69 to dispose of inner sediment and release air and gas as desired to prevent clogging and choking or the accumulation of foreign matter, said cocks being particularly useful during the operation of charging to permit a blowing through of the air and gas until the charge is clean and fresh and of the proper character.

Within the cylinder is a duplex differential piston, the same having duplicate sections which work in the duplicate sections of the cylinder. This piston is shown in detail in Figure 6. It has the main elongated sections 11 and 11^a, which are hollow and contain the tubular chambers C and D. At their inner ends these hollow sections 11 and 11^a are made integral with the enlarged portions or portions of greater diameter 10 and 10^a, which are hollow to provide inner fuel chambers F and G which are always in communication with the fuel chambers C and D respectively. Inside the chambers F and G are the integral spider or skeleton bosses 12 and 12^a into which the ends of the connecting rod 13 are screwed or otherwise centrally connected axially to the piston sections in order that these sections may be securely connected together in a single piston structure, the sections of the piston being thus placed tandem with each other. The rod 13 passes

through the central stationary box or bearing 15 in division part 14; the enlarged piston portions 10 and 10^a reciprocate in the explosion chambers A and B, and also in the barrel extensions or flanges 6 and 6^a on the explosion chamber walls 3 and 3^a; while the main parts 11 and 11^a of the piston reciprocate in the main chambers J and K of the cylinder bore.

In the walls of the cylinder sections 1 and 2 are the right-angled long ports 9 and 9^a which lead from the chambers J and K to the explosion chambers A and B and they serve as transfer ports to deliver the partly compressed charges of the mixture from the inner chambers of the piston to the explosion chambers; for the piston chambers are provided near their extreme outer ends with series of ports 19 and 20, which coincide at the ends of the stroke with the ports 9 and 9^a respectively, and hence permit the contents of the piston to be delivered to the explosion chambers. On one end or head of the piston in the percussion adaptation or form of the invention shown in Figures 3 and 6, and certain others, is a hardened block or hammer E designed to strike the percussion instrument or its carrier, while at the other end of the piston there is a head 47, beyond which is a cup or recess 60 formed in a tubular extension 46, into which screws a sleeve 45 for a purpose to be presently stated. Further, it should be noted that the piston in order to prevent leakage and secure close and uninterrupted compression with tight joints is supplied with suitable piston rings 51 on the end extension 46; piston rings 65 on the large middle portion 10, and piston rings 66 on the other large middle portion 10^a; piston rings 48 on the section 11 between ports 19 and portion 10, and piston rings 49 on the section 11^a between ports 20 and large portion 10^a; and rings 50 on the hammer member E; all being arranged in any desired way and of any type, number and quality. It will be seen in Figure 3 how effectively the long ports 9 and 9^a cover the rings 49 and allow said rings, and also rings 50, to protect said ports and the ports 19 and 20. The outer end of the engine has a head 52 screwed on the cylinder and provided with a convenient loop handle 52^a and also with straight handles 92 which serve useful purposes in enabling the machine to be manipulated when in use.

It will be thus seen that there are two initially-receiving preliminary-compression fuel chambers, each having its own inlet means which delivers first through the flanged extensions of the explosion chamber walls. The inlets therefore are the openings 7 and 7^a in the extensions 6 and 6^a. The fuel entering through port 7 fills the cylinder H and piston chambers F and C, these three spaces, H, F, and C forming a preliminary compression chamber in which a charge of fuel is

compressed after the piston moves and cuts off the port 7; and compression continues until the end ports 19 in the piston coincide with the firing chamber ports 9 and allow the partially compressed charge to escape into the explosion chamber A, where it flows in on top of the outgoing exhaust resulting from the previous explosion in chamber A. Similarly another preliminary compression chamber comprises cylinder space I and piston spaces G and D, and has a similar function to the one just described, its charge coming in through port 7^a and being expelled through ports 20 and 9^a into the explosion chamber B. The various piston and cylinder spaces are properly proportioned to provide the correct volume of mixture to generate the power needed. These spaces are also related to each other and to the inlets and exhausts in a manner to allow a clean and efficient operation, with great economy and power development.

The compressed charges in the explosion chambers A and B are fired when compression is complete by means of any suitable ignition apparatus, including spark plugs 64 and means for energizing the proper one at the right instant. One form of automatic means for closing a circuit and causing the plugs to produce sparks which I preferably employ is shown in Figures 1, 2, 3 and 16, which I will now describe. In the inner cylinder-fuel-chambers H and I are trip levers 18 and 18^a adapted to be struck and moved by the piston sections 10 and 10^a in their reciprocations. See Figure 3. These trip levers 18 and 18^a are arranged beneath the removable covers 16 and 16^a that belong to openings in the side or top of chambers H and I. Said levers are secured to short shafts 29 and 29^a, supported in the cylinder wall in insulated bearings 31. The levers have one end projecting downwardly in the piston path, while the other end has a toe 30 or 30^a that engages beneath the cover 16 or 16^a and keeps the levers in a position in which they are held by springs 28 and 28^a tensioned between the levers and the covers 16 and 16^a, which springs are compressed while the piston sections are in contact with and deflecting the levers 18 and 18^a to rock the shafts 29 or 29^a, and when this contact ceases the springs restore the levers to their normal position where the toes 30 and 30^a stop against covers 16 and 16^a. The shafts 29 and 29^a carry respectively the levers 32 and 32^a which are similar in form and function. I will describe one of them, say, lever 32 and its associated parts, all as fully shown in Figure 16. It is secured on shaft 29 by a screw 33 passing through the cleft end 34 of lever 32, so that the cleft end may be tightened or loosened. The opposite end oscillates in contact with a stem 39 belonging to a binding post 36 having binding

screws 38 and carried in an insulated sleeve 37 or bearing supported on projection 62 on the engine frame, said projection 62 having a set screw 63 passing through it and bearing against member 37. The end of lever 32 has an insulation or hard rubber segment 35 which at normal times touches the pin 39 and thus breaks the circuit, but when the lever 32 is vibrated slightly by the aforesaid movement of trip lever 18 due to contact of the piston therewith, the insulation 35 leaves its contact with pin 39 and the steel end of arm 32 contacts with pin 39 so that thus the circuit will be closed to allow current to pass and cause the spark plug in the proper explosion chamber to produce an igniting spark and set off the charge, for it will be seen that proper wires or other electrical conductors (not shown) will run from the binding nut 38 to one of the spark plugs 64. Ordinarily the trip levers will function to explode the charges in the firing chambers most remote therefrom, but obviously the arrangement of these details may greatly vary in different cases. 17 denotes a hood or shield used to cover and protect the plugs 64 and more or less of the detailed sparking mechanism which I have just described. The spark plugs 64 instead of being directly in the explosion chambers A and B are preferably placed somewhat off therefrom, so as to be in the cavities of ports 9 and 9^a, as this is found to create a more satisfactory combustion of the mixture, but I do not wish to be limited to this location.

As already stated one end of the piston carries a hammer head E, and the other end has an extension 46 containing a recess 60, and a sleeve 45 screws into extension 46, so as to leave this recess 60 at the inner end of sleeve 45. See Figure 13. On the end of the cylinder section 1 screws the rounded head 52 provided with a handle 52^a. Inside of head 52 is a passage lined with a conical washer 53, and an opening 93 is provided in the handle 52^a, in line with said washer. These features are employed to permit a starting device to be used to give the piston a few reciprocations in starting. An example of such a device is shown in Figure 13 and is only one of many that might be used, this being given for the sake of illustration merely. It consists of a long tube 54, that can be passed through the opening 93 in handle 52^a and also through the conical lining 53, until the end touches and is stopped by piston head 47. This tube has a handle 55. The inner end of tube 54 is notched or provided with an opening opposite groove 60. Within the tube 54 is a rod 57 provided with a right-angled finger 58 adapted to project through the end of the tube 54 sidewise and engage the piston by entering the recess 60. Also the handle 55 is provided with a spring 56 against which bears a trigger 59 forming a

part of rod 57 and being pivoted at 61 in the end of handle 55. Spring 56 normally presses against the trigger 59 so as to turn the attached rod 57 on pivot 61 and lift finger 58 out of recess 60. By drawing trigger 59 towards handle 55 with the finger and thus depressing spring 56, the finger 58 may be engaged with recess 60, and then by giving the starter a few movements back and forth by the use of the handle 55 the piston can be started to move in the cylinder and thus the engine set into operation. By releasing the finger from the trigger, the starter will automatically detach itself from the piston because the finger 58 will be lifted out of groove 60, and then the starter can be removed from the machine.

In Figures 3 and 11 I have shown clearly the mechanism for holding a drill or other tool so that it can be struck by the piston hammer E, and can also be rotated partially on each movement so that the drill bit will be more effectively presented to its work. The end of the cylinder section 2, at the end of the chamber K, is covered with a suitable screw cap 43, which has a circular opening therein so that the chuck or drill carrying member 41 can reciprocate through said opening, and carry with it the drill member 90 when it is operating upon its work, both the drill carrier 41 and the end of the drill 90 being in position to be struck by the piston hammer E, all as clearly indicated in the sectional showing in Figure 11. The drill proper 90 is polygonal in cross-section and slides in a similarly shaped passage in the carrier 41. The latter is provided with a series of inclined splines or ribs 89 that enter correspondingly inclined grooves in a nut or ring 42 having a pair of pivoted pawls 91 thereon, with or without spring devices, which pawls engage the inner ratchet teeth of a ring 87 that is secured by pins 88 to the inside of the wall of the cap 43. In a space between the inside of cap 43 and the carrier 41 is a spring 44 surrounding the carrier 41 and being tensioned against the ends of spline 89 and a portion of the adjoining face of the nut 42 and also against a shoulder inside of cap 43, the function of this spring being to return the chuck and its drill after each blow thereon by the hammer E. As the hammer strikes its blows on the face of block 41 and the end of the sliding drill member 90, when both are exposed to the blow, the spring 44 will be compressed as the carrier 41 moves downwardly against it and the drill 90 will be driven into the rock or other hard material which it is cutting, and after each blow the spring 44 will return the carrier and the drill to their former positions. At each reciprocation of the carrier 41 backwardly under the action of the spring the ring 42 will be revolved slightly in consequence of the action of the engaging ribs, for the pawls being in

engagement with the teeth of the ring 87, the carrier 41 and the ring 42 will be slightly rotated, just enough to change the position of the drill point, while on the opposite travel of the member 41 and the drill 90 toward the work, they will pursue a rectilineal movement without rotating for the pawls 91 will slip idly over a certain number of teeth, although it will be understood that if desired the parts may be so related that the partial rotation of the drill will take place when it is being driven toward its work and its return movement will be rectilineal and non-rotative. Further, the drill 90 is provided with a central longitudinal air passage 92 through which air pressure passes from chamber K to blow away the cuttings and dust caused by the action of the drill bit and thus constantly clean out the hole that is being drilled. Air pressure is provided in said chamber K by the suction action of the end of the piston in drawing air in through the inlet check valve 40. On the effective driving stroke of the hammer E this air is compressed and driven into the central passage 92 of the drill with the result as stated.

Thus far I have been describing the invention as built and adapted for use as a drill or percussion device, for use with rock, coal, concrete, or other hard material, the piston being a free piston, with one end constructed as a hammer or pounder to deal blows upon a tool or other object. But it will be clearly evident that the machine can serve equally well as an engine for various purposes, which will be connected to a crankshaft to actuate the same, and for this it is only necessary to add a connecting rod to the piston, and make such alterations as this change may necessitate.

I have illustrated an example of this engine in Figure 17, where the material parts of the cylinder and piston are the same as in the other figures. Thus the cylinder is duplex, with a dividing partition 14 between the sections, and on each side of the partition is a large cylinder-fuel-chamber into which the fuel supply is delivered by supply pipe 81 and its branches 80 and 78 and 79 which enter ports in the flanges 83 and 84 projecting from the walls of the explosion chambers into the fuel chambers. The duplex differential piston is the same as before, having elongated hollow portions 11 and 11^a together with hollow enlarged portions 10 and 10^a in the explosion chambers, the piston sections being connected by rod 13 for joint operation. The chambers in the piston sections deliver the partially compressed charges to the ports 9 and 9^a passing to the explosion chambers which have each an exhaust passage, as 82 and 85, which connect with a common discharge pipe 86; and there are similarly placed spark plugs 64. All these parts then are substantially the same as before,

but the piston instead of running freely, has an end member 77 to which a connecting rod 73 is pivoted. This rod carries a crank pin 75 in a crank arm on main shaft 76, the connecting rod, pin and crank being contained in crank case 72.

The operation of these and all forms of the engine and drill will be clearly understood by anyone skilled in the art from the foregoing explanation of the parts and their functions, and it is unnecessary to enlarge on the same. Many changes in details and proportions and the dimensions and relative location of the mechanical members may be made without exceeding the scope of the claims.

Having thus described my invention, what I claim as new and desire to secure by Letters Patent, is:

1. In an internal combustion engine, the combination of a sectional differential cylinder having explosion chambers, having exhaust means at one end and inlet means at the other end, a hollow differential piston containing differential inner fuel chambers and with enlarged portions operating in the explosion chambers, means for transferring the charges from the piston chambers to the explosion chambers, consisting of ports in the piston that deliver to the explosion chambers, large inner fuel supply chambers in the cylinder, communicating with the interior chambers in the piston, a stationary partition dividing said fuel chambers, means for transferring the charges from the cylinder-fuel-chambers to the piston-fuel-chambers, consisting of integral extensions on the explosion chambers that project into the cylinder-fuel-chambers, together with inlet means on the said extensions in the cylinder-fuel-chambers to alternately admit separate charges of the mixture into both sections of the cylinder, all the parts being so arranged as to provide preliminary fuel compression chambers in the interior of the cylinder and piston, from which the fuel mixture is transferred to the explosion chambers.

2. In an internal combustion engine, the combination of a sectional tandem differential cylinder having explosion chambers, provided with ported extensions, exhaust means for each explosion chamber in one end and a fuel intake at the other end, a differential piston containing differential inner fuel chambers and with enlarged portions operating in the explosion chambers, means for transferring the fuel charges from the piston chambers to the explosion chambers, consisting of lateral ports in the piston that intermittently open at one end of the stroke to deliver partially compressed fuel out of the piston into the explosion chambers, larger inner cylinder-fuel-chambers communicating with the interior chambers in the piston, a partition separating the fuel chambers and supporting a portion of the piston structure,

a piston rod passing through the partition and separate fuel inlet means for each cylinder-fuel-chamber controlled by the movement of the piston over the inlet ports in the ported extensions.

3. In an internal combustion engine, the combination of a duplex tandem differential cylinder having explosion chambers, with exhaust and inlet means, separated a distance from each other, central inner fuel supply chambers, and elongated main bore sections, a diaphragm located between the inner fuel supply sections, a duplex tandem differential piston having elongated hollow members and enlarged hollow inner sections which latter operate in the explosion chambers, said hollow members and sections forming compression chambers, a connecting rod for the two sections of the piston, means within the piston for holding the connecting rod, ported barrels in the cylinder-fuel-chambers of the same diameter as the explosion chambers and projecting from the wall thereof, the ports thereof being opened and closed by the moving piston, inlet means for the mixture entering said ported barrels, and ignition means in the explosion chambers.

4. In an internal combustion engine, the combination of a duplex, sectional, tandem, differential cylinder, each cylinder section having an inner central fuel portion of largest diameter, an intermediate portion of smaller diameter serving as a firing chamber, and an outer elongated main portion of still smaller diameter, a stationary partition separating the two central cylinder-fuel chambers, a duplex, sectional, tandem, differential piston in the cylinder, each piston section having an inner portion of larger diameter and a main long outer portion of smaller diameter, said piston-portion of larger diameter operating in the corresponding cylinder portion of intermediate size, and said long piston-portion of smaller diameter operating in the corresponding cylinder-portion of smallest diameter, the piston section being hollow throughout, and the chambers in their long main portions of smaller diameter communicating with chambers of larger diameter in the piston-portions of larger diameter, which latter open directly into the central cylinder-fuel chambers of largest diameter and remain always in open communication therewith, thus providing in each section of the piston and the co-operating section of the cylinder a preliminary fuel compression chamber comprising a large inner cylinder-fuel chamber, a chamber in the larger portion of the piston and a chamber in the main smaller portion of the piston, means connecting the piston sections together for joint reciprocation consisting of a rod passing through the stationary partition and connected to the two piston sections without interfering with the free movement of fuel in the fuel spaces, and means for transferring the fuel charges from the preliminary compression chambers to the fuel entrance into the firing chambers.

5. In an internal combustion engine, the combination of a duplex, sectional, tandem, differential cylinder, each cylinder section having an inner central fuel portion of largest diameter having fuel intake means, an intermediate portion of smaller diameter serving as a firing chamber, surrounding a part of the piston, and formed with a ported cylindrical extension that projects into the inner central cylinder fuel chamber to accommodate the travel of the piston section therein which covers and uncovers the port, and the

chambers into the firing or explosion chambers for a second and final compression before ignition.

5. In an internal combustion engine, the combination of a duplex, sectional, tandem, differential cylinder, each cylinder section having an inner central fuel portion of largest diameter, an intermediate portion of smaller diameter serving as a firing chamber and formed with a cylindrical extension that projects into the inner central cylinder fuel chamber to accommodate the travel of the piston section therein, and the wall of said firing chamber having an exhaust outlet near one end of the chamber and a fuel inlet near the other end, and said cylinder section having moreover an outer elongated main portion of still smaller diameter, a stationary partition separating the two central cylinder-fuel chambers, a duplex, sectional, tandem, differential piston in the cylinder, each piston section having an inner portion of larger diameter and a main long outer portion of smaller diameter, said piston portion of larger diameter operating in the corresponding cylinder portion of intermediate size and its projection into the cylinder-fuel-chamber of largest size, and said long piston-portion of smaller diameter operating in the corresponding cylinder-portion of smallest diameter, the piston sections being hollow throughout, and the chambers in their long main portions of smaller diameter communicating with chambers of larger diameter in the piston portions of larger diameter, which latter open directly into the central cylinder-fuel chambers of largest diameter and remain always in open communication therewith, thus providing in each section of the piston and the co-operating section of the cylinder a preliminary fuel compression chamber comprising a large inner cylinder-fuel chamber, a chamber in the larger portion of the piston and a chamber in the main smaller portion of the piston, means connecting the piston sections together for joint reciprocation consisting of a rod passing through the stationary partition and connected to the two piston sections without interfering with the free movement of fuel in the fuel spaces, and means for transferring the fuel charges from the preliminary compression chambers to the fuel entrance into the firing chambers.

6. In an internal combustion engine, the combination of a duplex, sectional, tandem, differential cylinder, each cylinder section having an inner central fuel portion of largest diameter having fuel intake means, an intermediate portion of smaller diameter serving as a firing chamber, surrounding a part of the piston, and formed with a ported cylindrical extension that projects into the inner central cylinder fuel chamber to accommodate the travel of the piston section therein which covers and uncovers the port, and the

wall of said firing chamber having an exhaust outlet near one end of the chamber and a fuel inlet near the other end, and said wall having long angular fuel ports therein leading to said fuel inlet and entering same so that the exhaust may occur as far as possible from the intake, and said cylinder section having moreover an outer elongated main portion of still smaller diameter, a stationary partition separating the two central cylinder-fuel chambers, a duplex, sectional, tandem, differential piston in the cylinder, each piston section having an inner portion of larger diameter and a main long outer portion of smaller diameter, near the end of which are fuel outlet ports which register at the end of the stroke with the aforesaid angular ports to deliver fuel to the firing chamber, and said piston portion of larger diameter operating in the corresponding cylinder-portion of intermediate size and its projection into the cylinder-fuel-chamber of largest size, and said long piston-portion of smaller diameter operating in the corresponding cylinder-portion of smallest diameter, the piston sections being hollow throughout, means consisting of a rod connecting the piston sections together for joint reciprocation, all arranged so that the fuel after being preliminarily compressed in the interior of the piston and the co-operating fuel chamber in the cylinder may be transferred to the firing chamber.

In testimony whereof I hereunto affix my signature.

JOHN V. RICE, JR.
